UNITED STATES PATENT OFFICE.

ADOLPH LOTHHAMMER, OF SACRAMENTO, CALIFORNIA.

DIGITORIUM.

SPECIFICATION forming part of Letters Patent No. 307,863, dated November 11, 1884.

Application filed February 27, 1884. (No model.)

To all whom it may concern:

Be it known that I, ADOLPH LOTHHAMMER, a citizen of the United States of America, residing at Sacramento, in the county of Sacramento and State of California, have invented 5 certain new and useful Improvements in Digitoriums, of which the following is a specification, reference being had therein to the accompanying drawings.

10 The object of my invention is to aid beginners, especially children and persons of little physical strength, in acquiring a practical knowledge of the piano, and to gradually strengthen the fingers and wrists while 15 acquiring such knowledge, at the same time to avoid the noise and annoyance of monotonous practice.

Figure 1 is a top view of the instrument when in use, showing the finger-board and 20 the regulating-screws. Fig. 2 is a front view of the finger-board, showing the keys, their pivots, the springs, and the point of their attachment to the rear end of the keys. Fig. 3 is a detailed view showing the regulating-screws, spring-bar, and springs.

A A, Fig. 1, is an ordinary inclosure or box, such as is used on a square piano, and intended for the same purpose—namely, that of inclosing the finger-board and its various 30 attachments. This inclosure is mounted upon a frame similar to and used for the same purpose as that of a piano.

B, Fig. 1, is an ordinary piano finger-board of similar construction, size, and similarly 35 located in the piano-inclosure A A, wherein *a* and *b*, respectively, designate the white and black keys. These keys are pivoted, respectively, at *a'* and *b'*, and they extend backward about the same length from the pivots as in 40 front of them, or to any required but to a uniform length.

C C, Fig. 3, are light metallic springs—one for each key, black or white—of uniform length, made of common spring-wire, in the 45 form of the human knee when about half bent, with one or more coils to each spring, whatever may be needed to give to each the required elasticity. The lower end of each spring is attached to the upper surface of the 50 rear end of each key, and the upper end to the under surface of the spring-bar D. In connection with the spring-bar it is the peculiar function of these springs to regulate the touch of the keys, and make it light or 55 heavy at the will of the operator.

D, Fig. 3, is a wooden bar, its length corresponding to the width of the digitorium, and of suitable thickness to give it strength—that is, from one-half to one inch thick from three to six inches wide, as use may 60 require. This bar, as stated above, rests upon the upper ends of the springs C C. By raising or depressing the bar the springs are relaxed or tightened.

E E, Fig. 3, are two upright screws, metallic or wooden, as best adapted to use, of moderate diameter, from one-half to an inch, according to the size of the digitorium. The thread is wrought on the lower ends and runs upward about one-half their length, or so far 70 as to relieve the springs from all depression by the bar D. At the upper terminus of the thread the screws are shouldered at E' E'. They pass through bar D near its ends and rest upon it by means of the shoulders E' E'. 75 The lower ends are fitted into nuts *ff*, hereinafter described. The upper ends should be so shaped as to facilitate turning them readily by hand, and may be ornamented at will. The screws control the bar D, which controls 80 the springs, and these regulate the touch of the keys. By this means the touch of the finger-board may be light or heavy, all parts alike, or one part light and the other heavy, at the option of the performer.

ff, Fig. 2, are two wooden or metallic nuts made to receive the screws E E, located on the floor and in the rear corners of the frame A A, of such height as is sufficient to admit all necessary perpendicular motion of the 90 screws.

When the finger-board is mentioned in the foregoing specification, the keys are meant—black and white, front and rear, and pivoted as described.

95

I claim—

A digitorium having the finger-board B, in combination with the metallic springs C C, spring-bar D, the upright screws E E, and nuts *ff*, all constructed and arranged, as and 100 for the purpose specified.

In testimony whereof I affix my signature in presence of two witnesses.

ADOLPH LOTHHAMMER.

Witnesses:

D. E. ALEXANDER,
F. A. ALEXANDER.
